UNITED STATES PATENT OFFICE

WILLIAM H. NICKERSON, OF BROOKLINE, MASSACHUSETTS

SHOE-SHANK STIFFENER

Application filed September 8, 1928. Serial No. 304,627.

This invention relates to a shank stiffener, adapted to be interposed between the shank portions of the insole and outsole of a shoe, and to support an external longitudinal ridge 5 on the shank portion of the outsole, the ridge conforming closely to the under surface of the stiffener, which is ridged to permanently support and maintain the predetermined form of the outsole ridge.

10 The object of the invention is to provide a shank stiffener which is ridged to support the forward end portion of an outsole ridge in position to adequately support the forward portion of the keystone arch of the wearer's 15 foot.

Of the accompanying drawings forming a part of this specification,—

Figure 1 is a bottom plan view of a shank stiffener embodying the invention.

20 Figure 2 is a section on line 2—2 of Figure 1.

Figure 3 is a bottom plan view, showing the portion of a welted shoe bottom with which the stiffener is associated, the outsole 25 and heel being omitted.

Figure 4 is a section on line 4—4 of Figure 3, and shows by dotted lines the ridged shank portion of the outsole.

Figure 5 is a section on line 5—5 of Figure 30 1.

Figure 6 is a view similar to Figure 5, showing a modification.

Figure 7 is a plan view of the shoe bottom, showing the outsole and the heel, the stiffener 35 being shown by dotted lines.

Figure 8 is an edge view of the shoe bottom, showing a portion of the upper.

The same reference characters indicate the same parts in all of the figures.

40 My improved shank stiffener 12, shown separately by Figures 1, 2, 5 and 6, is made preferably of sheet steel, and is adapted to be interposed between shank portions of the insole 13, and the outsole 14, of a welt shoe.

45 The stiffener has longitudinal edges 12^a and 12^b, which may be caused to conform to the curvature of the portions of the usual inseam stitch-securing lip 15, on the shank portion of the insole, the inner edge 12^a having a reentrant formation, as shown by Figures

1 and 3. The stiffener has its maximum width at its forward end, its rear end portion being considerably narrower and terminating in a narrow extension or tongue 12^c adapted to bear on the heel portion 13^a of 55 the insole. The length of the stiffener is such that its forward end is located in the ball portion of the shoe bottom. The stiffener may be secured to the insole by any suitable means, such as nails 17, driven through holes 60 in the inner end extension, or spurs 18, formed on the forward end, or by both nails and spurs.

The stiffener is provided with a longitudinal ridge 19, substantially parallel with the inner edge 12^a so that one side of the ridge has a reentrant formation. The ridge projects from the under side of the stiffener, and extends from a point in close proximity to the forward end, to, or nearly to the extension 70 or tongue 12^c. The ends of the ridge are inclined and merge into portions of the body of the stiffener. Said body includes longitudinally extending inner and outer wings projecting from opposite sides of the ridge and 75 transversely inclined to support the ridge offset below the shank portion of the insole 13. The inner wing is designated by 19^a and has the reentrantly curved edge 12^a. The ridge 19 is located substantially parallel with and 80 in close proximity to the edge 12^a, and wholly between said edge and the longitudinal median line of the stiffener, so that the inner wing 19^a is relatively narrow, and the outer wing 19^b is wider and presents a transversely 85 inclined longitudinally curved supporting surface coextensive with that portion of the wearer's foot which is directly under the longitudinal arch of the foot, and has no ridge, said supporting surface being stiffened by the 90 ridge 19. The cross-section of the ridged portion of the stiffener is preferably as shown by Figure 5, the ridge constituting a curved neck between and bulging outward from oppositely inclined portions of the stiffener, at 95 opposite sides of the ridge. The ridge may, however, constitute a neck which connects the oppositely inclined portions, without bulging therefrom, as shown by Figure 6.

The stiffener 12 is applied to the shank por-

tion of the insole 13, as indicated by Figures 3 and 4, before the outsole is applied, the welt 20 and upper 21 having been previously united to the lip 15 of the insole by the usual inseam stitches 22 (Figure 4). The outsole 14 is then applied and secured to the welt by the usual outseam stitches. The shank portion of the outsole is provided with an outwardly projecting ridge 33, which conforms 5 accurately to the stiffener ridge 19, and is supported by the latter. The forward end portion of the outsole ridge 23 is therefore located in the ball portion of the shoe bottom, between the longitudinal median line of the 10 shank portion of the outsole and the reentrantly curved inner edge of said shank portion, and in close proximity to said inner edge, 15 as indicated by Figure 7.

I claim:

20 A shank stiffener curved to conform to the curvature of the portion of a shoe bottom between the heel seat and ball, and including a longitudinally extending ridge and longitudinally extending inner and outer wings projecting from opposite sides of the ridge and 25 transversely inclined to support the ridge offset below the shank portion of an insole, the inner wing having a reentrantly curved edge, the ridge being located substantially parallel 30 with and in close proximity to said edge and wholly between said edge and the longitudinal median line of the stiffener, so that the inner wing is relatively narrow and the outer wing is wider and presents a transversely inclined longitudinally curved supporting surface coextensive with that portion of the 35 wearer's foot which is directly under the longitudinal arch of the foot, and has no ridge, said supporting surface being stiffened by the 40 ridge and located wholly at the outer side thereof.

In testimony whereof I have affixed my signature.

WILLIAM H. NICKERSON.
